GARMENT HANGER

Carl A. Isaacson, St. Paul, Minn.

Application December 6, 1943, Serial No. 513,077

10 Claims. (Cl. 223—94)

1

My present invention provides an extremely simple and highly efficient garment hanger that is adapted for use in hanging a wide variety of garments; such, for example, as coats, jackets, shirts, ladies' skirts and slips, and men's trousers.

The hanger of the present invention is truly universal in character and scope of application, since it may be quickly converted from a coat type hanger (meaning a hanger adapted to engage a top garment, such as a coat, jacket, shirt or the like, under the shoulder portions thereof) to a skirt type hanger (meaning a hanger adapted to be inserted into the flattened waist band of a skirt or the like and engage the same with expanding pressure).

Among the important objects of the invention is the provision of a garment hanger which can be collapsed or folded into a minimum of space for shipping and carrying.

Another object of the invention is the provision of a hanger that is readily adjustable to accommodate skirts, trousers, and the like of different waist band measurements.

Generally stated, the invention consists of novel devices, combinations of devices, and arrangement of parts hereinafter described and defined.

The above and other highly important objects and advantages of the invention will be made apparent from the following specification, claims, and appended drawings.

In the accompanying drawings, like characters indicate like parts throughout the several views.

Referring to the drawings:

Fig. 1 is a view in side elevation showing a hanger of the present invention with its parts positioned for hanging top garments, such as coats, jackets, and the like;

Fig. 2 is a view in side elevation showing the hanger folded for shipping or easy carrying;

Fig. 3 is a view looking downwardly on the hanger with the parts positioned as in Fig. 1, some parts being broken away;

Fig. 4 is a view in side elevation showing the hanger with its parts positioned for use as a skirt type of hanger and having part of the hook broken away;

Fig. 5 is an enlarged detail sectional view taken on the line 5—5 of Fig. 1;

Fig. 6 is an enlarged detail sectional view taken on the line 6—6 of Fig. 1;

Fig. 7 is an enlarged detail sectional view taken on the line 7—7 of Fig. 1;

Fig. 8 is a detail view of a spring friction-producing washer;

2

Fig. 9 is a fragmentary view illustrating use of the hanger as a trouser hanger; and

Fig. 10 is a fragmentary view looking downwardly on Fig. 9.

5 The hanger illustrated comprises a pair of rigid main arms 11 and a pair of rigid supplemental arms 12, which arms are all formed of flat strip material which may be wood, plastic, or metal. Wood, however, has been found to be the cheapest and, hence, the most practical from a commercial point of view at this time, although it is believed that in the future it may be commercially feasible to form the arms 11 and 12 of plastic material which would have the benefit of a superior eye appeal.

The main arms 11 are overlapped at their inner ends and pivotally connected together by a hollow rivet or the like 13, and the inner ends of the supplemental arms 12 are similarly over-

20 lapped and pivoted together by means of hollow rivets or the like 14. For use in suspending the hanger from a hook or bar, a wire hook 15 is provided at its lower end with a loop or eye 16 that works over the intermediate portion of the rivet 14 and between the inner ends of the supplemental arms 12, see particularly Figs. 1 and 3. The outer ends of the supplemental arms 12 are pivotally anchored to the longitudinally intermediate portions of the opposite arms 11 by rivets 25 or the like 17 at points equally spaced from the pivot point 13 of arms 11. With this arrangement, pivotal movements of the main arms 11 will produce a straight up and down movement between the pivots 13 and 14 so long as the free ends of arms 11 be maintained in a horizontal plane. In other words, with this arrangement, relative movement between the pivot points 13 and 14 will be in a straight line and will produce identical movements of the main arms 11.

30 40 For convenience in carrying and shipping, the hanger described may be folded into a very compact unit, as shown in Fig. 2, by moving the main arms 11 upwardly to the maximum extent about their pivotal connection 13.

45 When the hanger is to be used as a coat type hanger or upper garment hanger, the free ends of the main arms 11 are moved to their extreme positions shown in Fig. 1, wherein the inner ends of the main arms 11 rest against the bottom upper edge portions of the supplemental arms 12 at 18, and wherein the pair of arms 11 and the pair of arms 12 each form inverted V's. With the parts thusly positioned, as shown in Fig. 1, the device makes an ideal coat hanger when applied 50 55 through the neck portion of a coat with its arms

11 extending under the shoulders thereof, and is capable of supporting coats of great weight, since further downward movement of the free end portions of arms 11 is positively prevented by engagement of the pivoted end portions thereof with the under edges of arms 12 at 18.

To adapt the device for use in hanging skirts and the like of widely varying waist band diameter or girth, it is merely necessary to move the free ends of the arms 11 pivotally upwardly to a point whereat the free ends of said arms are above the pivot point 13 thereof and as much further in that direction as is necessary to fit the particular skirt involved, and reference is here made to Fig. 4, which shows the hanger as it would appear when applied to a skirt, shown only by dotted lines. To apply the device to a skirt, the hanger is applied within the waist band with the end of one of its arms 11 in engagement with one inside portion of the waist band, and then the hanger arms are spread until the free end of the other arm 11 comes into engagement with an opposite inside portion of the waist band and draws the skirt waist band taut. Of course, the greater the girth or diameter of the skirt waist band involved, the greater will be the spread of the arms 11 and vice versa. For the purpose of adapting the free ends of arms 11 to engage with equal frictional gripping action skirts of widely varying diameters, the free ends of arms 11 are preferably rounded on an arc that is tangent with the bottom edges of said arms and said rounded ends are preferably provided with circumferentially spaced grooves 19 forming intervening gripping teeth. In the illustration of Fig. 4, the hanger is shown with its parts positioned for engagement with a skirt of relatively large diameter, but it will be clear that the angle of divergence between the opposite arms 11 will be greatly decreased when materially smaller diameter skirts are used. Hence, with arms having arcuate ends as shown in the drawings, large diameter skirts are engaged close to the upper portions of the arcuate ends; whereas, smaller diameter skirts will be engaged nearer the bottom portions of the arcuate ends. With the arrangement shown, the weight of the skirt has a tendency to produce a spreading action of the arms 11; and, of course, this tendency is useful in keeping the hanger tightly engaged with the waist band of the skirt.

While it is important that the arms 11 and 12 be free for adjusting movements, it is also highly desirable that there be sufficient friction between the various pivoted elements to prevent accidental movements thereof while handling and to relieve heavy skirts of excessive expanding action of the arms. Hence, to insure a constant frictional drag against pivotal action, I preferably apply a suitable yielding friction-producing device at the pivot 13. In the preferred arrangement illustrated, this friction-producing device is in the nature of a conventional split spring lock washer 20 that is applied under the head 13a of rivet 13 and over a conventional flat washer 21.

To adapt the device of the invention to the hanging of men's trousers from the waist band, I preferably equip one of the arms 11 with a spring clip 22. This spring clip 22 is, in side elevation, in the form of an inverted U lying close against the side of one of the arms 11 with its outer end free and its inner end portion wound around the arm 11 and clinched thereinto at 23, see particularly Fig. 5. Not only does this clinching at 23 into the arm 11 positively anchor the spring clip

22 against sliding movements longitudinally of the arm, but it also provides a pivot point about which the free end of the clip 22 is adapted to move in a plane parallel to the side of arm 11 within limits caused by engagement of the clip with the top and bottom edges of the arm 11. The importance of this pivotal movement of the clip 22 will hereinafter be made apparent.

For use in hanging men's trousers from the waist band, the parts of the device are positioned much as for hanging a skirt, see Figs. 9 and 10, and are applied similarly within the waist band of the trousers. However, for hanging trousers, it is important that the trousers be maintained in a flat condition to maintain the pressing thereof, and this can only be done by turning in the waist band on lines co-extensive with the press lines in the fronts of the trouser legs to produce an inturned flap such as 24, Figs. 9 and 10. When this is done, the arms 11 are applied to the waist band of the trousers much as described in connection with a skirt, but with one of the arms 11 projecting alongside of the turned-in flap 24, which flap is clipped in position against the arm by means of the free end portion of clip 22, see particularly Figs. 9 and 10.

Now, as to the importance of the pivotal movements of the free end portion of clip 22 in the plane of the adjacent side of its arm 11, it may be said that for use as a coat hanger this clip, which then has no function, may be moved pivotally downwardly to a position below that shown in Fig. 1 and wherein it is largely below the upper edge of its arm 11; and for use as a skirt hanger, the extreme free end of clip 22 may be moved pivotally upwardly to a point substantially as shown in Fig. 4, wherein the said extreme free end is clear of the toothed arcuate end of its arm 11.

What I claim is:

1. A garment hanger comprising a pair of rigid main arms directly pivoted together adjacent their inner ends, and a pair of rigid supplemental arms pivoted directly to one another at a point directly above the point of pivotal connection of the main arms, said pair of supplemental arms diverging outwardly and downwardly from their point of pivotal connection and being pivotally connected at their lower ends each to the intermediate portion of a different main arm, and means suspending the hanger directly from the pivot between the supplemental arms.

2. A garment hanger comprising a like pair of garment-engaging main hanger arms having their inner ends overlapped and pivotally connected, a like pair of supplemental arms forming an inverted V of variable divergence, said like pair of supplemental arms having their upper ends overlapped and pivotally connected at a point above the pivot point of the main arms, the lower end portion of each supplemental arm overlapping and being pivotally anchored to the longitudinally intermediate portion of an opposite main arm, each supplemental arm overlapping the same side of the main arm as is overlapped by an opposite main arm, and means for suspending the hanger from the apex portion of the inverted V formed by the supplemental arms, whereby downward pivotal movements of the free end portions of the main arms will be limited to a point whereat the inner end portions of said arms move upwardly each into engagement with an opposite supplemental arm.

3. The structure defined in claim 2 in which the said means for suspending the hanger is in the nature of an open hook having its lower end

5

portion anchored to the pivot of the supplemental arms.

4. The structure defined in claim 2 in which the said means for suspending the hanger is in the nature of an open hook having its lower end portion anchored to the pivot of the supplemental arms, said hook being formed of wire and having its lower end portion disposed between opposite of the supplemental arms and turned about the pivot thereof.

5. The structure defined in claim 2 in which the free ends of the main hanger arms are rounded on arcs tangent to the lower edges of said arms.

6. The structure defined in claim 2 in which the free ends of the main hanger arms are rounded on arcs tangent to the lower edges of said arms, said arcuate ends of the main arms being notched at circumferentially spaced points to provide circumferentially spaced gripping teeth.

7. The structure defined in claim 2 in which the said main and supplemental arms are formed of flat strip material of like cross section.

8. The structure defined in claim 2 in further combination with a trouser flap-engaging clip in the nature of an inverted U lying flat against one side of the free end portion of one of said main arms, the inner end portion of said inverted U-shaped clip being anchored to the arm for limited pivotal movements of the free end thereof in a plane parallel to the plane of the side of the arm.

6

9. The structure defined in claim 2 in which the free ends of the main hanger arms are rounded on arcs having their centers near the upper edges of the arms.

5 10. A garment hanger comprising a pair of rigid main arms directly pivoted together adjacent their inner ends, and a pair of rigid supplemental arms directly pivoted together at a point directly above the point of pivotal connection of 10 the main arms, said pair of supplemental arms diverging outwardly and downwardly from their point of pivotal connection and being pivotally connected at their lower ends each to the intermediate portion of a different main arm, and a 15 hook connected to the pivot of the supplemental arms and extending upwardly therefrom.
